G. P. ABORN

FEED WATER HEATING SYSTEM

Filed Dec. 30, 1920

FIG. I.

George P. Aborn Inventor
By his Attorneys
F. J. Sawyer, Rice & Kennedy

UNITED STATES PATENT OFFICE.

GEORGE P. ABORN, OF BROOKLINE, MASSACHUSETTS, ASSIGNOR TO WORTHINGTON PUMP AND MACHINERY CORPORATION, OF NEW YORK, N. Y., A CORPORATION OF VIRGINIA.

FEED-WATER-HEATING SYSTEM.

Application filed December 30, 1920. Serial No. 433,973.

To all whom it may concern:

Be it known that I, GEORGE P. ABORN, a citizen of the United States, residing at Brookline, county of Norfolk, and State of Massachusetts, have invented certain new and useful Improvements in Feed-Water-Heating Systems, fully described and represented in the following specification and the accompanying drawings, forming a part of 16 the same.

This invention relates to improvements in feedwater heating systems.

It is the object of the invention to provide an improved feedwater heating system especially adapted for locomotive use, by which a supply of live boiler steam is fed to the feedwater heater through a supplementary boiler connection thereto controlled by the engine throttle through a suitable valve and 20 connections, so that the valve is opened when the locomotive throttle is closed and the locomotive is therefore drifting or standing, at which time there is, of course, no exhaust steam being supplied to the heater, 25 and by the same means the valve is closed so as to shut off such live steam supply to the heater when the throttle is opened and the locomotive is steaming, so that warm feedwater may at all times be available for 30 supply to the boiler by the feedwater pump, thus dispensing with an injector and avoiding the objectionable practice of pumping cool water into the boiler.

With the above objects in view, the invention will now be described in detail in connection with the accompanying drawing, and the features forming the invention will then be specifically pointed out in the claims.

Referring to the drawing—

40 Figure 1 is a plan view of a preferred arrangement of the improved system applied to a locomotive boiler; and

45 Figure 2 is a side elevation of a suitable feed water heater and its connections for use in this system.

50 Referring to the drawing, the letter A indicates generally the rear portion of a locomotive boiler, B the feed water heater and C the cold water supply pump for the heater which may also have combined there-

with the feed water pump D for delivery of the heater water to the boiler, and the heater system generally may be and is shown similar to that of U. S. Letters Patent 1,350,322, dated August 24, 1920. Cold supply water passing from the tender, not shown, through connection 12' is delivered by the cold water supply pump C to the feed water heater B to which the exhaust steam passes through connection 13 and the 60 heated water is withdrawn by feed water pump D and delivered to the boiler through connection 14, the pumps being actuated by a suitable auxiliary engine E having its valve chest F secured on one side thereof. 65 Suitable boiler connections 10 and 11 are provided for delivery of live steam respectively to the heater B and the valve chest F of auxiliary pumping engine E.

In order that the means for supplying 70 the heater with live steam and also cutting off such supply, may be controlled by the engine throttle 1, the latter is pivotally mounted on a bracket 2 secured to the boiler, such throttle being provided with an extension 3 on the end of which is a pin 4 free to ride in a slot in a lever 5 controlling a valve 6 mounted on the live steam connection 10 to the heater, the throttle being connected to valve rod α controlling admission of steam to the engine cylinders in the usual manner.

With the construction so far described, it will be obvious that when the engine throttle is closed, as indicated by position W, the extension 3 thereof will, through the pin and slot connection above described, throw the lever 5 of valve 6 in the opposite direction and thus open valve 6 and permit live steam to flow through pipe 10 to the heater B. 80 When the engine throttle is opened, as indicated by position X, the operation above described is reversed, the valve 6 is closed, and exhaust steam through a connection to the heater then heats the water therein.

To reduce the amount of flow through the feedwater heater when the locomotive throttle is either closed or open and there is no demand on the feedwater supply, there is located at a convenient point in the steam 100

connection 11 to supply pump C a manually controlled throttle valve 7, and this valve connects with a valve 8 in the live steam connection to the heater B. By the provision 5 of the connection between valves 7 and 8, consisting of pin and slot connection indicated generally at 9 and similar to that described above with reference to the engine throttle connection to valve 6, it will be seen 10 that when valve 7 is closed, with its throttle lever 12 in the position indicated at Y, the pump C is stopped or slowed down and valve 8 will be closed to cut off the supply of live steam to the heater, or, preferably, 15 nearly closed to a point where only a small amount of steam may pass to the heater B to heat the water therein when the locomotive throttle is closed and has opened the valve 6. It will be evident from the fore- 20 going that when the locomotive throttle is closed and the pump also shut off or slowed down, there will still be provided a sufficient flow of live steam to the heater to keep the water therein warm until the pump is again 25 started or speeded up, by moving the lever of valve 7 to the position indicated at Z, whereupon the live steam supply to the heater is dependent solely on the position of the engine throttle, as previously described. 30 It will be understood that various changes and modifications may be made in the in-

vention as above described and still be within the scope of the claims, and that the invention is not to be confined to use with locomotive feedwater heating systems, but may 35 be used with feedwater heating systems generally.

What is claimed is:

1. The combination with a boiler and its feedwater heater and supply pump therefor, 40 of a valve controlled live steam connection to said heater, connections between said valve and the engine throttle for controlling admission of live steam to the feedwater heater, and means cooperating with the supply pump steam valve for controlling the live steam supply to the heater. 45

2. The combination with a boiler and its feedwater heater connections, of live steam connection 10 for said heater, valve 6 controlling said connection, engine throttle 1 and connections for opening and closing said valve, valve 8 on said connection 10, feed water heater pump C and connections there- 50 to including a valve 7 controlling the steam supply to the pump, and connections be- 55 tween said valve 7 and valve 8 for opening and closing said valve 8 with valve 7.

In testimony whereof, I have hereunto set my hand.

GEORGE P. ABORN.
